WRAPPER TEAR TAB FORMING MECHANISM

Thermod Jensen, Laurelton, and Fred L. Waite,
Long Island City, N. Y., assignors to American
Machine & Foundry Company, a corporation
of New Jersey

Application September 2, 1949, Serial No. 113,882

26 Claims. (Cl. 53—61)

1

This invention relates to wrapping machines suitable for wrapping articles, such as loaves of bread, and more particularly to mechanisms for applying a relatively narrow tear strip to a continuous web, and forming an improved tear tab on each wrapper cut therefrom in order to make more easy the removal of a wrapper from an article enclosed therein. The invention also relates to improved methods of forming tear tab wrappers.

Devices for forming tear tab wrappers and packages are known in the wrapping art. However, these have been limited to wrapping machines in which successive wrappers to be used in packaging articles are the same, or substantially equal, in length. In such machines, it is customary to use mechanism for pre-cutting or punching holes at spaced points along a wrapper web, after which, a tear strip web is associated with the wrapper web, and when a wrapper is cut therefrom transversely across the cut or hole, it is provided with a tear tab.

The present invention relates to the formation of tear tab wrappers from a continuous composite tear strip wrapper web consisting of a continuous wrapper web having attached thereto a continuous tear strip web which extends longitudinally therealong. According to our invention, the composite tear strip wrapper web is cut, as by slitting transversely at desired points along its length in a limited zone adjacent the tear strip to cut the tear strip web. Following this operation, the composite tear strip wrapper web is cut transversely at a distance spaced inwardly from the above mentioned cut or slit without cutting off the portion of the tear strip which is to form the desired tear tab. In this manner, a tear strip wrapper having a tear tab extending freely beyond one end of the wrapper is produced.

Although our invention is adaptable for use in wrapping machines in which successive wrappers are of the same or substantially equal length, it is designed primarily for use in wrapping machines in which the length of wrapper web necessary to enclose an article is measured by the article to be wrapped and varies in accordance with the size of each article. In machines of this type, there is a real problem in obtaining satisfactory tear strip wrappers in which each tear tab projects substantially the same distance beyond the end of the wrapper with which it is associated.

The present invention solves this problem because it provides mechanism wherein regardless of variations in peripheral dimensions of articles

2

being wrapped, each tear strip wrapper is so formed that its tear tab extends substantially a uniform distance beyond the end of its wrapper when compared with other similar wrappers similarly formed. This insures that in the final wrapped packages, uniformity in appearance will be obtained.

It is therefore an object of our invention to provide improved mechanism for forming tear tab wrappers from a composite continuous tear strip bearing web in which the composite web is cut or slit transversely at spaced points adjacent the tear strip web, and the tear strip cut, and wherein the wrapper web is cut transversely at a distance spaced from said cut or slit without cutting the tear strip.

A further object of our invention is the provision of improved tear strip applying and tear tab forming mechanism capable of being used in wrapping machines in which varying lengths of composite tear strip wrapper web are fed in accordance with variations in sizes of articles being wrapped.

A further object is to provide novel wrapper web and tear strip feeding and handling mechanisms, and a novel type of cutting device for cutting the tear strip material and wrapper web, respectively, to form tear tab wrappers.

A further object of our invention is to provide tear tab forming mechanism which can be readily attached to and form a part of a wrapping machine in which each article being wrapped measures the length of wrapper to be wrapped thereabout, and thereby makes it possible to produce uniform packages having tear tabs of substantially equal lengths.

The invention also consists in the provision of mechanism for forming a continuous tear strip bearing wrapper web and making selective cuts as spaced points along the length of the composite wrapper web to produce wrappers having tear tabs extending freely beyond one cut end of each wrapper.

The invention also consists in the provision of a novel method of forming tear tab wrappers wherein regardless of variations in length of successive wrappers cut from an endless composite tear strip wrapper web, the tear tabs are substantially of equal length.

A further object consists in providing a novel method of applying tear strip material to wrappers in order to form improved tear tab packages.

A further object of the invention is to provide novel tear tab forming mechanism including means for cutting a tear tab strip to form a tear

tab, and also for cutting a wrapper transversely inwardly from its longitudinal edges to cut a wrapper from a continuous composite tear strip wrapper web without cutting the tear tab and thus form a wrapper having a separate tear tab extending beyond the cut end of the wrapper.

Other objects of our invention will be set forth in the following description and drawings which illustrate preferred embodiments thereof, it being understood that the above statements of the objects of our invention are intended generally to explain the same without limiting it in any manner.

In the accompanying drawings, which form a part of this specification, and in which like characters of reference indicate the same or like parts:

Figure 1 is a side elevation of a web feeding mechanism of a wrapping machine utilizing a preferred embodiment of the wrapper tear tab forming mechanism;

Figure 2 is a side elevation showing a preferred form of wrapper tear tab forming mechanism in detail;

Figure 3 is a side elevation of a modified form of tear tab cutting mechanism;

Figure 4 is a plan view of the web cutting and tear tab cutting mechanism as seen from line 4-4 of Figure 2;

Figure 5 is a side elevation of another modified arrangement of tear tab forming mechanism;

Figure 6 is a schematic end elevation of a wrapped package illustrating the relative arrangement of the wrapper web and tear tab;

Figure 7 is an isometric view of a wrapped package with its bottom seam turned upward to illustrate the tear tab projecting from said bottom seam; and

Figure 8 illustrates a single wrapper in conjunction with a tear tab after being cut from the continuous wrapper web.

Referring to the drawings, Figures 1, 2 and 5 illustrate a preferred form of our invention forming a part of a wrapping machine of the type in which an article to be wrapped is moved against the draped or depending leading or free end of a continuous wrapper web as it travels from an infeed conveyor, or other support, onto a lifter table where it is partially enclosed in the wrapper. The lifter table is then moved upwardly to deliver the partially wrapped article into a position proximate a wrapper foldway where the final enwrapping of the article takes place.

As shown, a continuous web of wrapping material W is supplied to the machine from a suitable source of supply, such as a roll R, Figure 1, suitably mounted between the side frames of the machine (not shown). A narrow continuous web of tear strip material S is also supplied to the machine from a roll T, and is fed into juxtaposition with the center portion or other desired portion of the wrapping material web. As illustrated in Figure 8, the tear strip material S lies along substantially the longitudinal center of the wrapper material web W. However, it is obvious that if desired, tear strip S could be located at some other position between the side edges of wrapper material web W. Tear strip S is secured or adhered to wrapper web W in order to prevent shifting during the web feeding operations, and also to insure that when the final package is to be opened, the tear strip cannot be pulled free of or removed from the package

without tearing the wrapper and thereby opening the package.

In order to effect the adherence of tear strip S to wrapping material web W, tear strip material web S, depending upon the kind or characteristics of wrapping material or tear strip material used, may be secured to the web by paste, or by heat sealing, or by application of a solvent to a localized surface of the wrapping material or tear strip with or without the application of heat. As shown in Figure 1, tear strip material S is fed in continuous web form through a paste or solvent applying device P which may be similar in construction and operation as that illustrated and described in co-pending Jensen and Drury application Serial Number 679,736, filed June 27, 1946, now Patent 2,538,564 issued January 16, 1951. As the tear strip material web passes through device P, paste or solvent, depending upon the type of material being used as a tear strip, is applied to one side of the tear strip material web S by a roller 10 in a paste or solvent well 12.

Where the wrapping material web W consists of waxed paper, well 12 and roller 10 are unnecessary and are removed from the paste or solvent applying device P. The desired adherence of tear strip material S to wrapper web W is effected by means of a sealing element, such as an electrically heated ironing shoe 14, which presses against the tear strip material web S and wrapping web W as they pass under a continuously rotating feed roller 16. In this manner, the application of heat energizes the wax coating on wrapping material web W, which coating, upon congealing, secures the tear strip web S to the wrapper.

Shoe 14 is mounted on the free end of an arm 18, pivotally supported on a stud 20, and is provided with a tension spring 22 serving the purpose of maintaining shoe 14 in steady contact with the juxtaposed wrapping material web W and tear strip material web S. Stud 20, which also supports a suitable guide roller 24, is mounted in frame bracket 26 of device P. Arm 18 carries another guide roller 28 which guides tear strip material web S into juxtaposed relationship with wrapping material web W as the latter passes underneath feed roller 16.

In case moisture proof cellophane web or a wrapping material having similar characteristics and a tear strip material web of moisture proof cellophane or material having similar characteristics are used, the two webs can be held in adhering relationship by heat sealing. It is preferred, however, to use also a solvent for energizing the coating on the webs such that they will adhere to each other, such as ethylene glycol monoethyl ether, commonly known and sold under the trade name "Cellosolve."

With all materials mentioned above, ironing shoe 14 may be employed to assure smooth adherence on tear strip material S to the wrapping material web W, but heating element 30 may be disconnected if desired. From what has been said above, it will be evident that by means of the mechanism described, wrapping material web W and tear strip material S are joined to form a composite tear strip wrapper web which is designated W¹.

In the event that an uncoated wrapping material web and/or an uncoated tear strip material web is used, well 12 is provided with a suitable adhesive, which is applied by roller 10 to one surface of tear strip material S moving into jux-

ta position with wrapping material web W. If desired, heated ironing shoe 14 may be used to accelerate the drying of the adhesive.

From feed roller 16, the composite tear strip wrapper web W¹ is guided over a roller 32, under a floating roller 34 and thence to another guide roller 36. The construction and operation of the several feeding and guiding rollers just described can be substantially the same as that shown in Gwinn Patent 1,626,409, and therefore further description and showing are deemed unnecessary.

From roller 36, composite tear strip wrapper web W¹ passes over the top of guide plate 38 of the wrapping machine to a pair of guide rollers 40 which support the leading end of the composite tear strip wrapper web W¹ in such manner that it hangs freely between an article to be wrapped, such as a loaf of bread, located on an infeed runway or support 42, and a lifter table 44.

The wrapping machine disclosed may be of the same general type as that disclosed in Jensen Patent 2,385,706. However, our novel mechanism may also find ready application in other types of wrapping machines in which tear tab wrapper forming mechanism is used.

In the machine illustrated in Figures 1, 2 and 5, lifter table 44 is provided with a back tension plate 46 and a top tension plate 48 supported thereon in a manner described in the Jensen patent. Table 44 is pivotally mounted on a shaft 50 suitably supported in the side frames of the machine (not shown). An adjustable connecting rod 52 is pivoted at one end to a lug 54 on the under side of lifter table 44, and pivotally connected at its other end to the free end of a cam lever 56 loosely mounted on a horizontal shaft 58 suitably supported in the side frames of the machine. To cam lever 56 is pivoted a cam roller 60 which tracks a cam 62 secured to the main cam shaft 64 of the machine suitably journaled in the side frames and driven from a suitable source of power (not shown). Cam 62 thus imparts an oscillating motion to cam lever 56, which in turn transmits this motion to the lifter table 44 through connecting rod 52 in proper timed relation with the other parts of the machine.

In the illustrated embodiment, lifter table 44 normally is maintained in an inclined position aligned with an inclined infeed runway 42 over which the loaves L are advanced into position to be delivered to the table 44 by pusher plates 66 projecting through a slot 68 in runway 42.

Pusher plates 66 are attached to an intermittently moving conveyor chain 70 of well known construction, such as shown in Jensen Patent 2,221,481, and therefore further description thereof is deemed unnecessary. One side of each loaf L slides along a guide plate 72 adjustably mounted on runway 42 and provided with a suitable cut-out (not shown) to allow passage of a reciprocating pusher plate 74 which pushes loaf L from the runway 42 onto the lifter table 44. Pusher plate 74 is affixed to the end of a rod 76, slidably supported in brackets 78 which are secured to cross bars 80 suitably attached to the side frames of the machine. Adjustably secured to rod 76 is a sleeve 82 which carries a stud 84 to which is pivoted one end of a link 86, the other end of which is pivoted to the free end of a lever 88, fulcrumed on a shaft 90, which receives its motion from a cam lever 92 through a connecting rod 94. Cam lever 92 is pivoted on a shaft 96 and carries a cam roller 98 which engages with a track formed on the periphery of

cam 100 mounted on main cam shaft 64. A tension spring 102 is employed to maintain the contact of cam roller 98 with cam 100. Spring 102 is anchored on one end to a stud 104 on lever 88, while the other end (not shown) is suitably secured to one of the side frames of the machine (not shown).

After lifter table 44 is moved to its horizontal loaf delivery position, as shown in Figure 2, additional composite tear strip wrapper web material is drawn downwardly over the rear side of a partially wrapped loaf L on the lifter table by a lap roller 106. Lap roller 106 is supported in the ends of a pair of arms 108 attached to a shaft 110 suitably supported in the side frames of the machine. Arms 108 are actuated by a connecting rod 112 pivotally connected to a lug 114 on the under side of one of the arms 108 and pivotally connected to the free end of a cam lever 116 fulcrumed on the shaft 58. Cam lever 116 carries a cam roller 118 which engages with a track formed on the periphery of a cam 120 mounted on the main cam shaft 64.

The tear tab wrapper forming mechanism includes a web cutting device C and a tear strip cutting device M (Figures 1, 2 and 4).

The tear strip cutting device M (Figures 1, 2 and 4) consists of a narrow preferably serrated cutting blade 152, which is mounted on the extreme free end of an armature 154 projecting from a solenoid 156 secured to a plate 158. Plate 158 in turn is fastened to the lower side of ledger plate 160. The latter is employed for the purpose of coacting with the web cutting blades 126 and 128 during the wrapper web cutting operation, and is secured to the lower side of a pair of lugs 162 projecting from the under side of lifter table 44. The tear strip cutter 152 is actuated during a momentary energization of solenoid 156 which causes the armature 154 and cutter 152 to move forward and cut the tear strip web S and also slit or cut a limited portion of the wrapper web W adjacent tear strip web W. To assure a rapid cutting action and return of cutter 152, the free end of the armature is provided with a cross bar 164 to the ends of which a pair of tension springs 166 is fastened. Tension springs 166 also are anchored to a pair of studs 168 held by and projecting from the solenoid supporting plate 158.

Figure 2 illustrates a suitable operating mechanism and circuit for actuating solenoid 156. Power is supplied through lines 170 and 172 to a micro switch 174 mounted on bracket 176 adjustably secured to a cross member 178 held by one of the side frames of the machine. Switch 174 is actuated by means of an adjustable stud 180 mounted on an arm 182 pivoted on a stud 184 secured to bracket 176. To facilitate setting or adjusting of stud 180, the latter is provided with a knurled head 186 and a lock nut 188. The free end of arm 182 is provided with a suitable cam-shaped tail 190 to facilitate momentary engagement of pusher arm guide rollers 192 as they pass over tail 190 and cause a momentary depression of arm 182 which, through stud 180, effects a temporary closing of micro switch 174 and thus a temporary energization of solenoid 156.

Each roller 192 is pivoted to a stud 194 held by a guide arm 196 mounted on a shaft 198 held by suitably spaced lugs 199 on a pair of spaced conveyor chains 200 constantly driven in synchronism with cam shaft 64 from the main drive of the machine (not shown). To each shaft 192 is

mounted a pair of well known pusher arms 202 employed for the purpose of pushing the partly wrapped loaf off the lifter table 44 and onto a delivery runway 204 as well as through a series of end fold plates (not shown) and sealing devices (not shown) to complete the wrapping of the ends of the package or loaf. Arm 196 and roller 192 are employed for the purpose of keeping the pusher arms 202 in vertical position during package conveying, which is achieved by roller 192 contacting a track 206 and a tension spring 208 (Figure 2) surrounding shaft 198, anchored to one of the lugs 199 and acting against one of the pusher arms 202, to maintain the contact of roller 192 with track 206 which is suitably mounted on brackets (not shown) attached to the side frames of the machine. Pusher arms 202 on conveyor chain 200, are of conventional construction and may be similar to those shown in Rundell Patent 1,590,208 or Schmitt Patent 1,851,295.

Web cutting device C consists of a pair of spaced arms 122 mounted on a horizontal cross shaft 134 supported in suitable bearings in the side frames of the machine. Shaft 134 is oscillated by means of a lever 136 secured thereto connected to one end of adjustable rod 138, the other end of which is attached to one arm of bell crank lever 140. To the other arm of bell crank lever 140 is pivotally connected one end of adjustable rod 142 having its other end connected to the free end of cam lever 144. Cam lever 144 carries a cam follower 146 which engages a cam track 148 in cam 150 secured to main cam shaft 64 of the machine. The upper free ends of arms 122 carry a transverse knife supporting bar 124 to which is attached a knife designated generally 125, which makes a transverse cut completely separating a tear strip wrapper from the composite tear strip wrapper web material W¹. This knife preferably consists of two elongated cutter blades 128, preferably provided with a plurality of serrated cutting teeth, attached to bar 124 in such a manner that the outer ends of the blades extend forwardly of the inner ends and in a broad V arrangement. If desired, cutter blades 128 may be of such length that their inner ends are in close adjacency and form a continuous V-shaped knife. As shown in Figures 4 and 5, however, in the knife 125, it is preferred to space the inner ends and mount a relatively short auxiliary center cutter blade 126 in the space between cutter blades 128. For best results, it has been found that an auxiliary cutter blade 126 having large spaced cutter teeth is desirable. The spacing of the points of the teeth of the auxiliary cutter blade 126 is such that in effect they straddle and do not cut the tear strip material S when cutter blade 126 is cutting the web of wrapping material W¹. As blade 126 cuts transversely the portion of the wrapper web closely adjacent the tear strip material S, the relatively flat sides of blade 126 act to free the portion of the tear strip adjacent the cut wrapper edge from the wrapper web. As shown in Fig. 8, it will be noted that the points of the serrated cut edges of a wrapper all lie in a substantially straight line and a tear tab E extends freely beyond one edge. In the center portion of the upper surface of auxiliary cutter blade 126, there is adjustably mounted a slitting knife 130 having two spaced vertical projecting cutter ears 132 which form longitudinal slits on opposite sides of the tear tab when the wrapper web is cut transversely by knife 125. The ar-

angement of the cutter blades 128 and auxiliary cutter blade 126 is such that when knife 125 is actuated to cut a wrapper from web W¹, the cut progresses inwardly from the longitudinal edges 5 of the web toward the center. This operation and the fact that an auxiliary cutter blade 126 is provided to cut the center of the main wrapper web and not the already cut tear strip, insures that only the wrapper web is cut transversely to form a cut tear strip wrapper web.

While the construction and operation of cutting blades 128 and 126, and the coaction of blade 126 with notch 210 effect the cutting of the wrapper web without again cutting that portion of the 15 tear strip which forms the tear tab, it is desirable that the bond between the tear strip web and wrapper web be such that there will be a separation of the two webs adjacent the tear strip web during the operation of the wrapper 20 knife 125. We have found that with the above described mechanism, this is readily effected, because at the time the wrapper is cut, the adhesive or solvent which is applied to the tear strip web material, has not firmly set or reached its full 25 strength and that the tear strip portion is displaced from the web as the wrapper knife 125 makes its transverse cut. Also, in the case of waxed paper or similar wrapper, the bond between the tear strip material and coated wrapper is 30 less than the strength of the tear strip material, and there is a separation between the two webs during the wrapper cutting operation which insures against cutting the tear strip material.

In the operation of the wrapping machine, an 35 article to be wrapped, such as a loaf L, is pushed by the pusher plate 74 from inclined runway 42 onto the lifter table 44, the motion being derived from cam 100 in the manner previously described. As loaf L is pushed onto the lifter table 44, it 40 presses the depending free end of composite tear strip wrapper web W¹ against back tension plate 46, the latter being displaced rearwardly, and top tension plate 48 wipes the wrapping material over the top of the loaf. Loaf L is thus partially 45 wrapped in the portion of web W draped in its path as mentioned heretofore with the tear strip web being located on the inner face of the web W¹. Cam 62 then actuates cam lever 56 and through connecting rod 52, raises the lifter table 50 44 to the level of delivery runway 204, as shown in Figure 1. At the same time and by reason of the upward motion of said lifter table, the web is pulled over plate 38, and lap roller 106, through the action of cam 120 upon cam lever 55 116 and connecting rod 112, previously described, moves downwardly, as illustrated in Figures 1 and 2. The machine is so timed that as soon as the lifter table 44, with the partly wrapped loaf, reaches its topmost position, a pair of pusher 60 arms 202 on conveyor chains 200 approach partially wrapped loaf L to push the same from the lifter table 44 onto the delivery runway 204. However, shortly before pusher arms 202 engage loaf L, guide roller 192, associated with these 65 pusher arms 202, engages tail 120 of switch control arm 122, thereby depressing the same and actuating and closing micro switch 174 which, as described heretofore, causes a momentary energization of solenoid 156, which in turn, causes the armature 154 and tear strip cutting blade 152 to move momentarily forward and cut tear strip S on the wrapper web W, and also make a narrow transverse slit N in tear strip wrapper web W¹, as illustrated in Figure 8. This tear strip cutting 70 and wrapper cutting occur shortly after lap roller

106 has passed the tear strip cutting blade 152, so that the portion of web W¹ extending downwardly from a partially wrapped article (Figure 1) above the lap roller, is stationary and under tension, which aids the cutting and slitting action. Lap roller 106, of course, continues to move downwardly and thereby pulls additional lengths of the webs forming tear strip wrapper web W¹ from reels R and T and through the machine. In the meantime, pusher arms 202 have engaged partly wrapped loaf L on lifter table 44 and start to push it from table 44 onto and about delivery runway 204. During this forward movement of loaf L by the pusher arms, and depending on how much of an overlap is desired of the bottom seams of the package, the web cutting blades 126 and 128 on arms 122 swing forwardly and in coacting with the ledger plate or shear bar 160, the wrapper web W is cut, as shown in dotted position in Figure 2, but, due to the arrangements of said cutting blades 128, 126, and the notch 210 (Figure 4) at the tear strip zone of the shear bar 160, as described above, the previously cut tear strip portion which forms the wrapper tear tab, is not cut off and extends freely beyond the end of the wrapper a distance equal substantially to the longitudinal spacing between knife 125 and cutter 152. As noted above, auxiliary knife blade 126, contacting the tab zone of the web, is provided with teeth of a much wider pitch than those of blades 128 to avoid cutting of the tear tab at this point. The wide pitch points of the teeth of auxiliary knife blade 126 straddle tear tab S as they pierce the wrapper during the operation of wrapper knife 125, and the relatively flat side edges of the pointed teeth of auxiliary knife blade 126 push or break the tear tab S free of the wrapper web without cutting it. Slitting knife 130, mounted on blade 126, effects two narrow vertical slits D at the cutting edge of the wrapper (Figure 8) which are parallel with and on each side of the tear tab to facilitate the starting of the tearing of the wrapper when the tear tab is pulled.

After the web is cut and the loaf is completely pushed from the lifter table 44 onto the delivery runway 204, the bottom seal of the package is completed and the tear tab E extends a desired length from the edge of the bottom seam F (Figure 7) with the tear strip web S being positioned between the periphery of the article and the wrapper (Figures 6 and 7).

Since bracket 176 is adjustably secured to cross member 178, the position of arm 182 can be adjusted to the left or right, as viewed in Figures 1 and 2. In this manner, the engagement of cam follower 192, associated with pushers 202, can be advanced or retarded and the length of tear tabs E can be made shorter or longer as desired.

A modified form of tear strip cutter actuating mechanism is illustrated in Figure 3. As shown in this figure, tear strip cutting knife 152 is secured to the bottom portion of a horizontal guide bar 220 slidably supported in a suitable bracket 222 secured to the lower side of the shear bar 160 attached to lugs 162 mounted on lifter table 44. Bar 220 is provided with a stud 224 which projects through a slot 226 in bracket 222 and engages a slot 228 in an arm 230 pivoted to a stud 232 held by bracket 222. Arm 230, through link 234, is connected to lever 236 mounted on a transversely extending shaft 238 supported by suitable bearings in bracket 222. At one end of shaft 238 is secured another arm 240, to the free

end of which is pivoted a generally U-shaped trip nose 242 which extends from and partly encloses the free end of arm 240 into the path of lap roller 106. Trip nose 242 is provided with a tension spring 244 and arranged and pivoted in such a manner that when an end of lap roller 106 contacts the top edge of trip nose 242, the latter remains rigid with arm 240 while being pressed downwardly by the descending lap roller 106, thus causing arm 240 also to be moved downwardly until lap roller 106, as it continues to move downwardly, moves out of engagement with trip nose 242. When lap roller 106 again ascends to return to its uppermost position, it engages the bottom edge of trip nose 242 and moves it upwardly with no effect on arm 240. Tension spring 242 causes the return of trip nose 242 to its normal position after the ascending lap roller 106 has passed.

In operation, the cutting of the tear strip S and piercing of the wrapper web W are effected by the rather rapidly downward motion of the lap roller 106 and its quick depressing action upon nose 242 and arm 240 which, through shaft 238, lever 236, link 234 and arm 230, causes a quick momentary forward motion of bar 220 and knife 152. The latter cuts the tear strip in the same manner as if mounted on the armature of solenoid 156, described heretofore. Upon the return of the lap roller 106 to its upward position, the latter swings trip nose 242 upwardly against the pull of spring 244.

While Figures 1 and 2 illustrate the tear strip cutting device M located closely adjacent web cutting device C, the former may be located elsewhere in the web path of the machine as long as the location corresponds with the proper relative distance to a line where the web is cut later on by the web cutting mechanism C. This modification of our invention is shown in Figure 5 in which tear strip cutting device M is shown located above web guide plate 38. In this form of the invention, guide plate 38 is provided with a suitable slot 250. Knife 152 cuts the tear strip of composite tear strip wrapper web W¹ while web W¹, extending along plate 38, is at rest. At this moment, lap roller 106 dwells temporarily and the web cutting also takes place at this time. The tear strip cutter 152 in Figure 5 is connected to the projecting end of an armature 252 of a solenoid 254 adjustably secured to a supporting plate 256, which in turn is also adjustably mounted on a suitable bracket 258 attached to the bottom of the delivery runway 204. The solenoid is momentarily energized through the same type of microswitch as shown in Figures 1 and 2 and is actuated by the pusher guide arm 196 and roller 192 as the result of the depression of tail 190 of switch lever 182 by roller 192.

The invention above described may be varied in construction within the scope of the claims, for the particular embodiments selected to illustrate the invention are but a few of the possible concrete forms which our invention may assume. The invention, therefore, is not to be restricted to the precise details of the structures shown and described.

What we claim is:

1. In a wrapping machine for applying a wrap per and a tear strip about an article to be wrapped, means for draping the leading end of a composite wrapper web including a continuous wrapper web having a continuous web of tear strip material attached thereto in the path of movement of said article, an article lifter table,

means for moving said article against said draped leading end of said composite wrapper web and partially enwrapping said article therein as it moves onto said lifter table; means for moving said lifter table to locate said partially enwrapped article at a delivery station, conveying means for moving said partially wrapped article off said lifter table, a first cutter for substantially simultaneously cutting said tear strip and a limited portion of said wrapper of said composite web adjacent said tear strip, a second cutter for cutting only said wrapper web of said composite web transversely at a position spaced longitudinally from and discontiguous with said cut made by said first cutter ahead of said cut in said wrapper web after said partially wrapped article has been moved off said lifter table, and means for actuating said first cutter in advance of the actuation of said second cutter to form a tear tab wrapper having a tear tab adapted to extend beyond and entirely free of the cut end of said wrapper.

2. In a wrapping machine, having mechanism for partially enwrapping an article in the leading end of a continuous composite tear strip wrapper web, said wrapper web comprising a continuous wrapper web and a continuous tear strip web affixed thereto, means for locating said partially wrapped article at a wrapper cutting station, a web cutter located at said station, a tear strip cutter, and mechanism for operating said cutters to cut said web and tear strip material, and said wrapper web only, respectively, at longitudinally and discontiguously spaced points along said composite web, thereby forming a wrapper having a projecting tear tab disassociated from and extending freely beyond the cut end of said wrapper.

3. In a wrapping machine, a source of supply of continuous wrapping material, a source of supply of continuous relatively narrow tear strip material, means for adhering said tear strip material to said wrapping material to form a continuous composite tear strip wrapper web, mechanism for partially enwrapping an article in said continuous composite tear strip wrapper web, a tear strip cutter, a transverse wrapping material cutter spaced from said tear strip material cutter, and means operative after said article has been partially enwrapped in said wrapper web for operating said cutters to cut said tear strip web and said wrapper of said composite web, and said wrapping material only, respectively, at longitudinally discontiguously spaced points along said wrapper web.

4. The method of forming tear tabs on the wrappers of wrapped articles, such as wrapped loaves of bread, comprising feeding a composite wrapper web consisting of juxtaposed, continuous webs of wrapping material and relatively narrow tear strip material to a wrapper applying station, partially wrapping said composite wrapper web about an article to be wrapped with said tear strip material positioned between said article and wrapping material, substantially simultaneously cutting said tear strip material and a limited portion of said wrapping material of said composite web adjacent said tear strip material, and subsequently transversely cutting the entire width of said wrapping material web only of said composite web transversely with a substantially unbroken cut at a point spaced longitudinally from and discontiguous with the cut end of said tear strip material to form a tear tab wrapper.

5. The method of forming tear tab wrappers for use in wrapping articles, such as loaves of bread, comprising securing a continuous web of tear strip material to a continuous web of wrapping material to form a composite continuous tear strip wrapper web, substantially simultaneously cutting a limited portion of said web adjacent said tear strip material and said tear strip, and then transversely cutting the entire width of said wrapping material web at a point spaced longitudinally from and discontiguous with said first-named cut inwardly from its opposite longitudinal edges to cut said wrapping material web only and form a tear tab wrapper, whereby the cut end of said tear strip material web is disassociated from said wrapper and forms a tear tab extending freely beyond the end of said wrapper.

6. The method of forming tear tab wrappers for use in wrapping articles, such as loaves of bread, comprising securing a continuous web of tear strip material to one face of a continuous web of wrapping material to form a composite continuous tear strip wrapper web, substantially simultaneously severing said tear strip material and cutting a limited portion of said wrapping material of said composite web adjacent said tear strip material, and then cutting said composite tear strip wrapper web transversely at a position spaced longitudinally from said cut portion of said tear strip material web and substantially simultaneously rupturing the bond between said tear strip material and wrapping material webs to free said tear strip from said wrapping material and prevent it from being cut when said wrapping material is cut to form a wrapper having a tear tab positioned on said same face of said wrapper and extending freely beyond one cut end of said wrapper.

7. In a machine for wrapping articles, such as loaves of bread, mechanism for applying the free end portion of a composite wrapper web comprising a wrapper web and tear strip web affixed thereto and extending longitudinally therealong between the sides of said wrapper web about an article to be wrapped, means for cutting said tear strip web and a portion only of said wrapper adjacent said tear strip, and means for cutting said wrapper web only transversely to form a substantially unbroken cut across the entire width of said wrapper at a point longitudinally spaced from and discontiguous with said cut tear strip portion.

8. In a wrapping machine for wrapping articles, such as loaves of bread, a supply of wrapping material, a supply of tear strip material, guides for feeding said wrapping material and tear strip material into juxtaposition, a sealing unit including means for causing said tear strip material to adhere to said web material, means for moving an article to be wrapped to a wrapping station, means for applying the leading end of said wrapping material with said tear strip material adhering thereto and in uncut condition about said article to be wrapped, cutting means for cutting said tear strip material, a cutter for subsequently cutting said wrapper material only at a point spaced longitudinally from said cut tear strip material to form a tear tab wrapper partially enveloping said article, and means for moving said partially wrapped article from said station.

9. In a machine for wrapping articles, such as loaves of bread, a source of supply of continuous wrapping material, a source of supply of continuous tear strip material, mechanism for simul-

aneously feeding said wrapping material and said tear strip material from said sources of supply, mechanism for joining said wrapping material and said tear strip material together, means for guiding the leading end portion of said joined wrapping material and tear strip material to a wrapper applying station, means operative at said station for applying said leading end portion of said continuous wrapping and tear strip material about an article to be wrapped, means for holding said tear strip bearing wrapper taut, longitudinally spaced cutters, and means for operating said cutters for cutting said taut tear strip material and a limited portion only of wrapping material adjacent said tear strip material substantially simultaneously, and for cutting said wrapper completely across at a point spaced longitudinally from and discontiguous with said cut tear strip material to form a wrapper partially enwrapping said article provided with a tear tab extending freely outwardly from the cut edge of said wrapper.

10. In a wrapping machine, a source of supply of continuous wrapping material, a source of supply of continuous relatively narrow tear strip material, means for adhering said tear strip material to said wrapping material to form a continuous tear strip wrapper web, a tear strip cutter, a transverse wrapping material cutter spaced from said tear strip cutter, means for operating said tear strip cutter to substantially simultaneously cut said tear strip material and a limited portion only of said wrapping material adjacent said tear strip material, and means for operating said wrapping material cutter to cut said wrapping material only with substantially a straight uninterrupted line across the entire width of said wrapper web at a position spaced longitudinally along said wrapper web and thereby separate from said continuous tear strip wrapper web a tear tab wrapper having a tear tab extending freely beyond said cut edge of said wrapper.

11. A wrapping machine for wrapping articles such as loaves of bread, comprising a lifter table, a source of supply of continuous wrapping material web, a source of supply of continuous tear strip material web, means for joining said tear strip material web to said wrapping material web and thereby forming a continuous composite tear strip wrapper web, feeding means for drawing off wrapping material web and tear strip material web from said sources of supply and positioning the leading end of said composite tear strip wrapper web in the path of movement of an article onto said lifter table, means for moving an article against said leading end of said composite tear strip wrapper web onto said lifter table and partially wrapping said article, a delivery station, means for moving said lifter table to said delivery station, means for pulling slack in said continuous composite tear strip wrapper web extending from said partially wrapped article, a tear strip material cutter, a wrapper cutter, a conveyor for moving said partially wrapped article from said lifter table, means actuated by said conveyor for operating said tear strip cutter to cut said tear strip, and means for actuating said wrapper cutter to cut said wrapping material only of said composite tear strip wrapper web at a point longitudinally spaced from said tear strip.

12. In a machine for wrapping articles, such as loaves of bread, mechanism for applying a wrapper and a tear strip about a loaf of bread to be wrapped, a tear strip cutter comprising a knife blade, a support for said blade, a device for mov-

ing said support to cause said blade to cut said tear strip and a limited portion only of said wrapper adjacent said tear strip, a wrapper knife, means mounting said wrapper knife at a distance spaced longitudinally from said tear strip cutter, and means for actuating said wrapper knife to make a complete transverse cut cutting said wrapper only along a substantially straight line and at a point discontiguous with said first cut and thereby form a wrapper having a tear tab projecting from the cut end of said wrapper.

13. A tear tab wrapper forming device for a wrapping machine comprising a support, a tear tab cutter mounted on said support, said cutter including a solenoid, a tear tab cutting blade attached to the armature of said solenoid, a wrapper cutting knife mounted at a distance spaced from said tear tab cutter, means for feeding a continuous composite tear strip wrapper web past said tear tab cutter and said wrapper cutting knife, means for operating said solenoid to cause said tear tab cutter blade to cut substantially simultaneously both said tear strip and a limited portion of said web of said composite web adjacent said tear strip, and means for subsequently actuating said wrapper cutting knife to cut said web only with a substantially straight line cut completely across the entire width thereof and separate from said composite tear strip wrapper web a wrapper having a tear tab extending beyond one cut end of said wrapper.

14. The mechanism defined in claim 12, wherein said wrapper knife includes a plurality of elongated transversely positioned serrated cutting blades, all located in substantially the same cutting plane, means mounting said blades in substantially the form of a wide V with the outer ends of said blades extending forwardly of the inner ends thereof, whereby during the wrapper cutting operation said web is cut inwardly from the longitudinal edges thereof.

15. The mechanism defined in claim 12 wherein said wrapper knife includes two main elongated serrated cutter blades having inner and outer ends, a movable support for said blades, means mounting said blades on said support with said inner ends in spaced relation, and an auxiliary wrapper cutter blade located in said space between the inner ends of said main blades.

16. The mechanism defined in claim 12 wherein said wrapper knife includes two transversely positioned main cutting blades having their outer ends mounted forwardly of their inner ends, and an auxiliary cutter blade positioned between the inner ends of said main cutting blades, said auxiliary knife being provided with wide pitch cutting teeth, whereby said wide pitch teeth enter and cut said web on opposite sides of said tear strip only and the relatively flat sides of said teeth free said uncut tear strip from engagement with said wrapper.

17. In a wrapping machine for applying a wrapper and a tear strip about an article to be wrapped, means for draping the leading end of a continuous composite tear strip wrapper web in the path of movement of an article to be wrapped, said composite web comprising a continuous web of wrapping material and a continuous web of tear strip material extending longitudinally therewith, an article lifter table, a conveyor for moving an article against said leading end of said composite web and partially enwrapping said article as it moves onto said lifter table with the tear strip material of said composite web between said article and wrapping ma-

terial, means for moving said lifter table to locate said partially wrapped article at a delivery station with said composite web extending downwardly from said partially wrapped article; a lap roller, a wrapper cutter, a tear strip cutter mounted below said wrapper cutter, means for moving said lap roller against said wrapper extending from said partially wrapped article to supply additional composite web, means for actuating said tear strip cutter after the operation of said lap roller to cut said tear strip material web and make a transverse cut in a limited portion only of said wrapping material web of said composite web adjacent said tear strip web, and means for actuating said wrapper cutter to cut said wrapping material only along a substantially straight uninterrupted line of cut at a point spaced longitudinally from and discontiguous with said transverse cut in said wrapper web and above said transverse cut to form a wrapper having a wrapper tear tab extending freely beyond the cut end of said wrapper partially enwrapped about said article.

18. The mechanism defined in claim 17 including a second conveyor having a plurality of spaced article engaging pushers for moving partially wrapped articles off said lifter table, a solenoid operatively connected to said tear strip cutter, a circuit including said solenoid, a switch in said circuit, a switch closing arm, and means on each of said pushers for moving said arm to close said switch and make said circuit to energize said solenoid and thereby actuate said tear strip cutter.

19. In a machine for wrapping articles, a source of supply of a continuous composite tear strip wrapper web, mechanism for partially wrapping the leading end of said web about an article with the trailing end of said web extending outwardly away from said partially wrapped article, means for positioning said partially wrapped article at a delivery station, a lap roller, means for moving said lap roller downwardly against said outwardly extending trailing end of said wrapper to pull additional wrapper web from said source of supply, a tear strip cutter, a movable support for said cutter, an operating member for moving said support to advance said cutter to cut said tear strip and make a transverse slit in said wrapper web of said composite web, means mounting said operating member in the path of movement of said lap roller, means for moving said lap roller downwardly to pull additional wrapper web from said source of supply and engage and depress said operating member to actuate said tear strip cutter, a wrapper cutter, means mounting said wrapper cutter at an operating position located longitudinally between said delivery station and said tear strip cutter, and means for actuating said wrapper cutter to cut said wrapper only transversely between said partially wrapped article and the cut end of said tear strip.

20. In a wrapping machine having a lifter table, an article receiving station and an article delivery station, a shear bar carried by said lifter table, a tear strip cutter mounted on said shear bar, a wrapper cutter adapted to coact with said shear bar, means for moving an article against the leading end of a continuous composite tear strip wrapper web onto said lifter table at said receiving station and partially wrapping said article in said wrapper web, and means for moving said lifter table and partially wrapped article to said delivery station, means for actuating said tear strip cutter to cut said tear strip and make a transverse slit in a portion of said wrapper web.

adjacent said tear strip, and means for moving said wrapper cutter into operative relation with said shear bar to cut said wrapper web only, and thereby provide said partially wrapped article with a wrapper having a tear tab extending freely beyond the cut end of said wrapper.

21. The mechanism defined in claim 20 wherein said shear bar is provided with a central elongated notch, and said wrapper cutter comprises elongated serrated cutting blades and an auxiliary cutting blade having wide pitch cutting teeth mounted centrally of said elongated serrated cutting blades, said auxiliary cutting blade coacting with said notch in said shear bar to cut said wrapper only and maintain said tear strip material uncut.

22. The mechanism defined in claim 21 including longitudinal slitter devices mounted at the ends of said auxiliary cutting blade, said slitters being constructed and arranged to form longitudinal slits in the end of said wrapper at the sides of said projecting tear tab.

23. In a wrapping machine, a source of supply of continuous wrapping material, a source of supply of continuous relatively narrow tear strip material, means for adhering said tear strip to said wrapping material to form a continuous composite tear strip wrapper web, a wrapper cutter for cutting a substantially unbroken transverse cut entirely across said wrapping material, a tear strip cutter spaced longitudinally from said wrapper cutter, means mounting said tear strip cutter between said wrapper cutter and said source of supply, means for operating said tear strip cutter to substantially simultaneously cut said tear strip material of said tear strip wrapper web and form a transverse slit in a limited portion only of said wrapping material of said composite tear strip wrapper web, means for actuating said wrapper cutter to cut said wrapping material only of said tear strip wrapper web at a point in advance of said slit in said wrapper and discontiguous therewith to form a wrapper having a tear tab extending freely beyond the cut end of said wrapper.

24. In a wrapping machine for wrapping articles, such as loaves of bread, a lifter table, an article receiving station, an article delivery station, means for moving said lifter table between said receiving station and said delivery station, a conveyor including a plurality of spaced pushers adapted to move past said delivery station and remove partially wrapped articles from said lifter table, means for pushing an article against the draped leading end portion of a continuous composite tear strip wrapper web onto said lifter table at said receiving station to partially wrap said article in said leading end portion of said composite tear strip wrapper web, a shear bar carried by said lifter table, a tear tab cutter carried by said lifter table beneath said shear bar, a wrapper cutter coacting with said shear bar, an electric circuit, a solenoid mounted on said lifter table connected in said circuit, said tear tab cutter including a blade attached to the armature of said solenoid, a switch in said circuit, a switch closing arm, an actuating member carried by each of said spaced pushers adapted to depress said arm when said lifter table is located at said delivery station and thereby close said switch and energize said solenoid, whereby said tear strip cutter cuts said tear strip, and means for actuating said wrapper cutter to cut said wrapper web only above said tear strip cut-

ter to provide said partially wrapped article with a tear tab wrapper.

25. Tear tab wrapper forming mechanism for a wrapping machine comprising a movable article support, a shear bar mounted on said support, a wrapper cutter coacting with said shear bar, a tear tab cutter mounted on said movable support beneath said shear bar, means for locating a continuous composite tear strip wrapper web consisting of a continuous wrapping material web and a longitudinally extending relatively narrow tear strip material web adhered thereto between said wrapper cutter and shear bar, means for actuating said tear tab cutter to cut said tear strip material of said tear strip wrapper web and form a transverse slit in a limited portion only of said wrapping material of said tear strip wrapper web adjacent said cut tear strip, and means for operating said wrapper cutter for transversely cutting said wrapping material only of said tear strip wrapper web above said slit in said wrapping material to form a tear tab wrapper having a tear tab projecting freely beyond the cut end of said wrapper.

26. A wrapping machine for wrapping articles such as loaves of bread, comprising a lifter table, a source of supply of continuous wrapping material web, a source of supply of continuous tear strip material web, means for joining said tear strip material web to said wrapping material web and thereby forming a continuous composite tear strip wrapper web, feeding means for drawing off wrapping material web and tear strip material web from said sources of supply and positioning the leading end of said composite tear strip wrapper web in the path of movement of an article onto said lifter table, means for moving an article against said leading end of said composite tear strip wrapper web onto said lifter table and partially wrapping said article, a delivery station, means for moving said lifter table to said delivery station, means for pulling slack in said continuous composite tear strip wrapper web extending

from said partially wrapped article, a shear bar mounted on the underside of said lifter table, a wrapper cutter coacting with said shear bar, a support mounted on said shear bar, a movable slide carried by said support, a lever connected to said slide, a tear strip cutter attached to said slide, a shaft mounted in said support, a bell-crank lever mounted on said shaft, a link connected to said lever and one arm of said bell-crank lever, a pivoted nose mounted on the other arm of said bell-crank lever, resilient means normally holding said nose against said arm of said bell-crank lever, said nose projecting outwardly into the path of movement of said slack pulling means, mechanism for moving said slack pulling means downwardly into engagement with said nose to effect the movement of said cutter blade to cut said tear strip material web and a portion of said wrapping material web, and means for moving said wrapper cutter to cut said wrapping material web only above said cut tear strip and form a tear tab wrapper for said partially wrapped article.
